UNITED STATES PATENT OFFICE

JOHN W. S. HODGDON, OF LONG BEACH, CALIFORNIA

DESIGN FOR A DIRIGIBLE AIRPLANE

Application filed October 14, 1929. Serial No. 33,029. Term of patent 3½ years.

To all whom it may concern:

Be it known that I, JOHN W. S. HODGDON, a citizen of the United States, and a resident of Long Beach, in the county of Los Angeles and State of California, have invented a new, original and ornamental Design for Dirigible Airplane, of which the following is a specification, reference being had to the

accompanying drawing, forming a part thereof.

The figure in the drawing is a perspective view of my dirigible airplane.

I claim:

The ornamental design for a dirigible airplane as shown.

JOHN W. S. HODGDON.
